KARL SITTIG, OF PHILADELPHIA, PENNSYLVANIA, ASSIGNOR TO WESTINGHOUSE ELECTRIC & MANUFACTURING COMPANY, A CORPORATION OF PENNSYLVANIA

OVERSPEED GOVERNOR

Application filed April 17, 1930. Serial No. 445,233.

My invention relates to an overspeed governor, and it has for its object to provide an overspeed governor having improved operation.

Prime movers of certain types, for example, steam turbines, are customarily provided with two governing devices, one of which is a regulating governor for regulating the admission of motive fluid in response to an operating condition of the prime mover, for example, the speed thereof. The regulating governor may be responsive to the speed in addition to another operative condition. The other governing device is an overspeed governor, which guards against a dangerous overspeed in case of failure of the regulating governor or other speed-limiting means. It operates at a predetermined overspeed of about 10% above the normal operating speed, acting on a separate quick-closing throttle valve to effect complete closing movement thereof and preferably embodies a trip mechanism which must be reset before the throttle valve can be reopened.

Inasmuch as the tripping mechanism must be reset before operation of the prime mover can be resumed, it is desirable to control the admission valve so as to maintain the speed below the predetermined overspeed, thereby avoiding operation of the overspeed governor.

In accordance with my invention, I provide an overspeed governor comprising an element movable in accordance with the speed of the prime mover, and I also provide means which is effective upon movement of said element in response to an overspeed above the governing range of the regulating governor but below the usual overspeed at which the throttle valve is tripped, and operates to effect closing of the admission valve normally controlled by the regulating governor. Still further means are provided for tripping the throttle valve upon movement of the element in response to speed of the prime mover above the usual overspeed of about 10%.

The above and other objects are effected by my invention as will be apparent from the following description and claims taken in connection with the accompanying drawing,

forming a part of this application, in which:

The single figure is a diagrammatic view of the governing mechanism, the overspeed governor being shown in section on an enlarged scale.

Referring now to the drawing more in detail, I show an elastic fluid turbine 10 supplied with motive fluid through a conduit 11. The motive fluid first passes through a throttle valve 12, which is fully open in the normal operation of the prime mover, and thence through an admission valve 13, which regulates the motive fluid admission in response to the speed or other operating condition of the prime mover.

The admission valve 13 is operated by any suitable regulating mechanism known in the art. For example, a fluid pressure governor 14 is shown, which may be of the type described and claimed in the patent of H. F. Schmidt, No. 1,583,767, issued April 14, 1925. The governor 14 includes a fluid actuated operating piston 41, constituting part of a fluid pressure relay and connected to the admission valve 13 through a lever 15 fulcrumed at 16. A spring 17 acts on the lever 15 in the direction for closing the admission valve 13.

The throttle valve 12 is operated by a piston 18 disposed in a cylinder 19 and to which it is connected by a rod 21. The piston 18 is biased in the direction for closing the throttle valve 12 by a spring 22, and a passage through the piston 18 is provided at 23. A screw threaded stem 24 extends through the upper end wall of the cylinder 19 and is adapted to close the upper end of the passage 23. A hand wheel 25 is fastened on the stem 24 for operating the same.

To provide fluid pressure varying as the square of the speed of the turbine 10, I provide a pump including an impeller 26 mounted directly on the turbine shaft 27 and discharging into a conduit 28. An auxiliary pump 29, arranged to discharge into the conduit 28, is also provided to supply fluid pressure when starting the prime mover. Check valves 31 and 32 are provided to prevent flow from either pump to the other.

The overspeed governor may be housed in a structure unitary with the cylinder 19, and

in the present embodiment it includes a cylindrical chamber 33 formed by the cylinder structure. A passage 34 communicating with the lower end of the cylinder 19 is also provided and communicates with an annular recess 35 in the cylindrical chamber 33. The conduit 28 communicates with the lower end of the chamber 33, and a restricted orifice 36 provides a restricted flow of fluid through the passage 34 to the lower end of the cylinder 19.

The chamber 33 is also provided with an annular recess 37 communicating through a conduit 38 with any suitable mechanism for effecting complete closing of the admission valve 13. This mechanism may include a valve 39, which is adapted to release fluid pressure from that side of the operating piston 41 embodied in the governor 14 on which fluid pressure acts on the operating piston to move the admission valve 13 in opening direction, thereby rendering the spring 17 effective to close the admission valve 13.

The valve 39 is operated by a piston 42, biased in the direction for opening the valve 39 by a spring 43. A restricted flow of fluid from the conduit 28 into the conduit 38 is provided through a conduit 44 containing a restricted orifice 45, and the fluid pressure in the conduit 38 normally acts on the piston 42 to close the valve 39, permitting operation of the admission valve 13 by the governor 14 in response to the speed of the prime mover.

The chamber 33 is further provided with fluid discharge recesses 46 and 47, communicating with a drain conduit 47'. The upper end of the chamber 33 communicates with the inlet of the pump 26 through a conduit 48.

Disposed within the chamber 33 is a pilot valve 49, biased upwardly by the impeller pressure in the lower end of the chamber 33 and downwardly by a spring 51 connected at its lower end to a spring holding member 52. The latter is adapted to be adjusted to change the setting of the spring 51 by a stem 53, on which the member 52 is screw threaded. The pilot valve 49 is also biased downwardly by the pump inlet pressure, in order to negative the variations in the pump discharge pressure caused by variations in the pump inlet pressure.

The pilot valve 49 is formed with annular recesses 54 and 55. When the prime mover is operating at the desired normal operating speed, the pilot valve is disposed with the recesses in the position shown. In this position, the recess 54 communicates with the annular row of ports 37, and the recess 55 communicates with the annular recess 35. The upper edge of the recess 54 is spaced by a small amount from the lower edge of the recess 47, so that as the pilot valve 49 moves upwardly, the recess 54 places the recess 37 in communication with the recess 47. The upper edge of the recess 55 is spaced from the

lower edge of the recess 46 by a greater amount, so that upon a still greater upward movement of the pilot valve 49, the recess 55 places the recesses 35 and 46 in communication.

A manually operated valve 56, controlling the discharge of fluid from the lower end of the cylinder 19 to a drain conduit 57, may also be provided.

The operation of the above-described apparatus is as follows:

In normal operation, the throttle valve 12 is maintained in fully opened position by the piston 18, which is held at the upper end of its travel by fluid pressure developed by the impeller 26. The admission valve 13 is controlled by the governor 14 to regulate the admission of motive fluid to the turbine 10.

The governor maintains the speed within a predetermined range, the maximum speed of which may be, for example, 4% above normal operating speed. The pilot valve 49 is in the position shown on the drawing, cutting off the escape of fluid from the passage 34 and from the conduit 38. The pressure in the latter maintains the valve 39 closed, permitting the piston 41 of the governor to be actuated to operate the admission valve 13.

In case of failure of the governor 14 to restrict the speed of the turbine, the fluid pressure developed by the pump 26 increases and moves the pilot valve 49 upwardly by an amount proportional to the increase in fluid pressure. At a predetermined overspeed which is above the maximum speed provided by the governor 14 and below the overspeed at which the throttle valve 12 is closed, for example, 6% above normal operating speed, the pilot valve 49 is brought to position placing the recesses 54 and 47 in communication. The fluid pressure in the conduit 38 is released, and the spring moves the piston 42 downwardly. The valve 39 is opened, releasing fluid pressure from above the operating piston 41. The spring 17 is thereupon effective to move the valve 13 to closed position, in an endeavor to check further increase in speed.

Should this action prove inadequate to restrict increase in speed, and the speed be increased by more than 10% above the normal operating speed, the pilot valve 49 moves upwardly to place the recess 55 in communication with the recess 46. The fluid pressure in the lower end of the cylinder 19 is thereupon released through the passage 34, and the spring 22 acts on the piston 18 to move the throttle valve to closed position. The admission of motive fluid is now cut off at a second point, and cannot be restored until the throttle valve operating mechanism is reset.

When the turbine slows down again and the escape of fluid from the passage 34 is cut off at the recess 46, the fluid escapes

through the passage 23, the upper end of which has been opened by movement away from the stem 24. To reopen the throttle valve, it is necessary to lower the stem 24 by 5 rotation of the hand wheel 25 until it abuts the piston 18 and closes the passage 23. The throttle valve may then again be opened by slowly raising the stem 24, permitting the fluid pressure to raise the piston 18.

10 The purpose of interposing the valve 39 is to immediately provide ample discharge area. As the recesses 54 and 47 come into communication, a slight discharge opening provided by the recesses is sufficient to release the pressure of the fluid in the conduit 38, whereupon the valve 39 provides ample discharge opening to release the fluid pressure above the piston 41.

By manually opening the valve 56, the 20 throttle valve may be tripped closed independently of the action of the overspeed governor.

The advantage of the above construction is that a separate control is provided for 25 effecting complete closing of the admission valve when the speed begins to increase above the normal range. If closing of the admission valve 13 is sufficient to restrict the speed below the 10% overspeed, operation of the 30 throttle valve is avoided, and, upon return to normal speed, admission of motive fluid to the turbine is restored without the necessity of resetting the throttle valve operating mechanism.

35 While I have shown my invention in but one form, it will be obvious to those skilled in the art that it is not so limited, but is susceptible of various changes and modifications without departing from the spirit of my 40 invention, and I desire, therefore, that only such limitations shall be placed thereupon as are imposed by the prior art or as are specifically set forth in the appended claims.

What I claim is:

45 1. The combination with a prime mover having an admission valve and a quick-closing throttle valve, of a governing system therefor comprising means for regulating the admission valve in accordance with a variable 50 operating condition of the prime mover, and emergency governor means responsive to an operating condition of the prime mover and operative to effect closing of the admission valve upon a predetermined departure of said 55 last-mentioned operating condition from normal and to effect closing of the throttle valve upon a predetermined departure from normal greater than the first-mentioned departure.

60 2. The combination with a prime mover having an admission valve and a quick-closing throttle valve, of a governing system therefor comprising means for regulating the admission valve in accordance with a variable 65 operating condition of the prime mover, and

an overspeed governor operative to effect closing of the admission valve upon a predetermined overspeed and to effect closing of the throttle valve upon a predetermined overspeed greater than the first-mentioned overspeed. 70

3. The combination with a prime mover having an admission valve and a quick-closing throttle valve, of a governing system therefor comprising a governor responsive to the speed of the prime mover for regulating the admission valve, and an overspeed governor operative to effect closing of the admission valve upon a predetermined overspeed and to effect closing of the throttle valve upon a predetermined overspeed greater than the first-mentioned overspeed. 75

4. The combination with a prime mover having an admission valve and a quick-closing throttle valve, of a governing system therefor comprising a governor responsive to the speed of the prime mover for regulating the admission valve, and an overspeed governor operative to effect closing of the admission valve upon a predetermined speed above 80 the governing range of the first-mentioned governor and to effect closing of the throttle valve upon a predetermined overspeed greater than said predetermined speed. 85

5. The combination with a prime mover having an admission valve and a quick-closing throttle valve, of a governing system therefor comprising a governor responsive to an operating condition of the prime mover for regulating the admission valve, means providing a fluid pressure varying as the speed of the prime mover, and an overspeed governor comprising an element movable in response to said fluid pressure, means responsive to limited movement of said element to effect closing of the admission valve, and means responsive to further movement of said element for effecting closing of the throttle valve. 90 100 105

6. The combination with a prime mover having an admission valve and a quick-closing throttle valve, of a governing system therefor comprising a governor responsive to the speed of the prime mover for regulating the admission valve, means providing a fluid pressure varying as the speed of the prime mover, and an overspeed governor comprising an element movable in response to said fluid pressure, means responsive to limited movement of said element to effect closing of the admission valve, and means responsive to further movement of said element for effecting closing of the throttle valve. 110 115 120

7. The combination with a prime mover having an admission valve and a quick-closing throttle valve, of a governing system therefor comprising means for regulating the admission valve in response to the speed of the prime mover, means providing a fluid pressure varying as a function of the speed of 125 130

the prime mover, and an overspeed governor comprising an element responsive to said fluid pressure and a spring biasing said element for determining the position thereof in accordance with the varying fluid pressure, means responsive to a position of said element corresponding to a predetermined overspeed above the governing range of the governor for effecting closing of the admission valve, and means responsive to a position of said element corresponding to an overspeed greater than the first-mentioned overspeed for effecting closing of the throttle valve.

In testimony whereof, I have hereunto subscribed my name this second day of April, 1930.
